[57] CLAIM

The ornamental design for a manipulative water game
housing, substantially as shown and described.

DESCRIPTION

FIG. 1 is a perspective view of a manipulative water
game housing showing my new design;

FIG. 2 is a rear elevational view thereof;

FIG. 3 is a left side elevational view thereof;

FIG. 4 is a bottom plan view thereof.

The bottom of the claimed design is substantially flat
and unornamental.
